UNITED STATES PATENT OFFICE.

ALEXANDER S. CHESSIN, OF NEW YORK, N. Y.

GYROSCOPIC STABILIZER.

Application filed February 3, 1917. Serial No. 146,321.

My invention relates to devices for steady-ing bodies subject to swinging, rolling, or other oscillating motions or disturbances, and has for its object to provide an im-
proved, efficiently operating stabilizer of the gyroscopic type.

Two specific embodiments of my invention will now be described with reference to the accompanying drawings, and the novel fea-
tures will then be pointed out in the ap-
pended claims.

In said drawings, Fig. 1 is a somewhat diagrammatic elevation showing one form of my improved stabilizer, with parts in sec-
tion; Fig. 2 is a plan view, with a diagram of the electrical connections; Fig. 3 is a detail longitudinal vertical section of one of the electromagnetic clutches employed in the device shown in Figs. 1 and 2; Fig.
4 is a fragmentary elevation, with parts in section, showing another form of my in-
vention; Fig. 5 is a partial section taken on the line 5—5 of Fig. 4; and Figs. 6 and 7 are detail face views illustrating certain
25 contacts used in conjunction with the forms of my invention shown in Figs. 1 to 3 and 4 and 5 respectively.

Referring particularly to the form of my invention illustrated by Figs. 1, 2, 3, and 30 6, A designates an axle or fulcrum station-
ary relatively to the body (say, a ship's hull) to be steadied; generally, this axle or fulcrum will be normally horizontal and will extend in the longitudinal central plane
35 of the ship or other body. On this axle or fulcrum is mounted the carrier B, which in the arrangement just referred to will there-
fore be capable of swinging in a transverse plane. As shown, the upper ends of the car-
rier are made with alining bearings B', hori-
zontal in the normal position illustrated, and receiving transverse alining trunnions
40 C' projected from opposite ends of a frame C. In this frame a gyroscopic rotor D is
45 supported with its spindle D' to turn about an axis which is perpendicular to the axis of the trunnions C' and intersects the ful-
crum axis A as well as the axis of said trunnions (or of the bearings B'). The axis of
50 the trunnions C' lies in a plane perpendicu-
lar to the fulcrum axis A. A universal or Cardanic connection thus exists between the frame C and the body carrying the fulcrum
A. The detail construction of the rotor D and the means for operating it, being well-
known in the art, have not been shown in

the drawings; as a rule, an electrically ac-
tuated rotor is preferred. Of course, this
gyroscopic rotor will be made of proper di-
mensions to produce the desired steadyng
effect, it being understood that the swing-
ing motions of the body to which the device
is attached, will set up reactions by the gyro-
scopic rotor D tending to restore such body
to its normal position, in accordance with
well-established principles.

In order to control the gyroscopic effect of
the device, I have provided a special actuat-
ing clutch mechanism in connection with
the trunnions C', which mechanism com-
prises an operating member on each side, in
axial alinement with the respective trun-
nions C'. In the embodiment of my inven-
tion illustrated by Figs. 1, 2, 3, and 6, each
of the trunnions C' carries rigidly an op-
erating pulley E and a counterbalancing
pulley E'. Each of the operating pulleys E
is connected by a (normally horizontal) belt
F with an actuating pulley G, made wholly
or partly of iron or other magnetizable ma-
terial, so that the said pulley may serve as
an armature to be attracted by one or the
other of two electromagnets H, H' between
which said pulley G is located. The pulley
is not only adapted to rotate about its axis,
but is also capable of a longitudinal sliding
movement toward one or the other of said
electromagnets. In the particular construc-
tion shown, the pulley G is mounted to slide
and to turn on a stationary sleeve J secured to
the core or hub of the stationary electromag-
net H, and is normally held in a central posi-
tion between the two electromagnets, by coiled
springs K. Through the electromagnets H,
H' and through the sleeve J extends the
drive shaft L, rotated permanently in any
suitable manner, and upon this shaft is se-
cured rigidly, as by means of a key, the ro-
tary electromagnet H'. The opposing faces
of the pulley G and of the electromagnets H,
H' are suitably shaped (and lined, if de-
sired) to form clutch surfaces; in the par-
ticular case illustrated, these surfaces are
conical. To prevent sticking of the pulley
or armature owing to remanent magnetism,
the clutch surfaces of the two electromagnets
may be on cover-plates h, h' of non-mag-
netizable material, and direct contact may
be avoided between the armature and the
magnetizable portions or annular cores of
the two electromagnets. The electromag-
net coils H'', H' are preferably coaxial with

the drive shaft L. One end of each coil H'', H² is shown connected with the core of the respective magnet, and through it and the shaft L, with the frame or bearing M in which said shaft is journaled; the other end of each coil H'', H² is connected with an (insulated) binding post N, N' respectively. Each of the counterbalancing pulleys E' is connected by a (normally horizontal) belt F' with an idler pulley O journaled in suitable stationary brackets O'. The object of the pulleys E', O and belt F' is simply to balance or neutralize the pull exerted by the driving belt F on one side of the apparatus or the other, whichever belt happens to be in operation. Normally (with the operating pulleys G in the position shown in Fig. 3) the belts F are free, but under certain conditions, as described hereinafter, one pulley G or the other is thrown into clutch engagement with the rotary electromagnet H' adjacent to it, and in this case the corresponding belt F becomes operative as described below.

Each of the trunnions C' carries rigidly a contact strip or brush P, insulated from the trunnion, as by a sleeve P'. This brush is adapted to engage two segmental contact-plates Q, Q' (see Fig. 6), the space between said plates being preferably a little wider than the brush P, so as to break the contact between the brush and one plate before the brush engages the other plate in passing from one plate to the other. The plates Q, Q' are stationary, being carried by supports R made of rubber or other insulating material. The contact plates Q, Q' are provided with binding posts S, S' respectively, and are set flush in the supports R. Engaging members T, preferably made yielding, for instance by means of springs U, are adapted to be engaged by the carrier B, and specifically by the bearings B', at the same time that the brushes P engage the respective contacts Q, Q', thus relieving the said contacts from undue pressure. The supports R may be inclined slightly, as indicated (somewhat exaggerated) in Figs. 1 and 2, so as to be approximately perpendicular to the position of the respective trunnion C' at the time the brush P engages the contacts Q or Q'.

Broadly speaking, it is desired to have the apparatus operate in such a manner that when the brush P engages the contact Q, the corresponding rotary electromagnet H' will be energized so as to attract the armature or pulley G and cause it to rotate, the motion being transmitted by the belt F to the pulley E so as to swing the frame C about the axis of the trunnions C'. Should the brush P be carried beyond the contact Q, and pass onto the contact Q', this will cause the closing of another circuit to energize the stationary electromagnet H so as not

only to unclutch the pulley G from the rotary electromagnet H', but to lock such pulley positively against rotation, by its engagement with said stationary electromagnet. In the drawings, I have shown an arrangement in which the circuit closed by the brush P does not include the coils H'', H² of the electromagnets H, H' respectively, but includes relays controlling separate energizing circuits; thus I am enabled to use a stronger current for energizing the electromagnets than the current employed in the brush circuit. In Fig. 3, I have shown the binding post N' connected by a wire a with another binding post N'' on a ring V secured rigidly to the rotary electromagnet H' but insulated therefrom, said ring being in permanent engagement with a stationary contact spring W carried by the bearing M but insulated therefrom, and provided with a binding post W'.

The electrical connections may be arranged as indicated diagrammatically in Fig. 2. From one terminal of the battery X wires b, b' lead to the respective brushes or contact-makers (switches) P. The other battery pole has four connections or wires c, c', c'' and c* leading to relays Y, Y', Y'', and Y* respectively. The wires c' and c* are connected with the contact plates or segments Q at the respective sides of the apparatus. The other wires, c and c'', are connected with a double-pole switch Z, by means of which said wires may be connected, simultaneously, with wires d and d' respectively, connected with the contact segments Q' at the respective sides of the device. Each of the four relays is adapted to close, when energized, a circuit including the coil H'' or H² of one of the four electromagnets H, H'. For this purpose, each of the relays, when energized, will connect a contact e, e', e'', e* respectively, with another contact f, f', f'', f* respectively. The contacts e, e'' are connected by wires g, g'' respectively, with the binding posts N of the respective (stationary) electromagnet coils H''. Similarly, the contacts e', e* are connected by wires g', g* respectively, with the binding posts W' of the two contact springs W. The contacts f, f', f'', f* are connected by wires i, i', i'', i* respectively with one pole of a source of electricity, for instance a main j connected, say, with the ship's dynamo. From the other main j' wires k, k' lead to the two bearings or frames M.

When, owing to a transverse swing of the carrier B, the brush or contact strip P on one side of the apparatus is brought into engagement with the conducting segment or plate Q on that side (the brush being normally in registry with the upper end of such segment, see Fig. 2), the circuit of the battery X will be closed, say through b, P, Q, and c'. The relay Y' being thus energized,

will establish an electrical connection between the contacts e' and f' , thus closing the following circuit: Main j , wire i' , contacts f', e' , wire g' , contact spring W , ring V , post N'' , wire a , post N' , coil H^2 of the corresponding rotary electromagnet H' , core of said electromagnet, shaft L , bearing M , wire k , and thus back to the other main j' . The electromagnet H' being thus energized, will 5 attract the armature or pulley G and couple it with the said rotating electromagnet. Through the medium of the belt F the pulley E will be operated to turn the frame C with the gyroscopic rotor D about the axis 10 of the bearings B' , thereby automatically producing a definite precession of the rotor D , this particular precession lasting until the contact between P and Q is broken. The breaking of this contact may occur 15 either owing to the return transverse swing of the carrier B about the axis A (which will be the case generally), or owing to the fact that the swinging or turning of the frame C about the axis of the bearings B' 20 will carry the brush P beyond the lower edge of the contact segment Q and into engagement with the non-conducting or insulated support R . The purpose of the support R is partly to carry the conducting segments Q and Q' , and partly to provide an 25 extended bearing surface, flush with said segments, on which the brush P may pass when it goes beyond the edge of one of said segments, so that the brush P can readily 30 return to a position facing the conducting segment Q . As soon as contact is broken 35 between P and Q , the corresponding magnet H' is de-energized, and the springs K will bring the operating pulley G to the 40 disengaged position shown in Fig. 3. From that time on, the swing of the frame C is due exclusively to the action of the engaging member T . The precession due to the 45 action of this member T is also automatic but generally of different magnitude from the precession due to the action of the belt F . In Letters Patent of the United States No. 1,134,439 issued to me on April 6th, 1915, I have referred to the precession due to the 50 action of an engaging member such as T , as the "normal" precession. On the other hand, the precession due to the action of the driving belt F need not be normal, but is controlled automatically, and the speed of 55 this precession may be made greater or smaller than normal, by properly adjusting or selecting the velocity at which the shafts L and electromagnets H' rotate. Thus this precession is not only absolutely under control, but its speed may be predetermined to 60 comply with variable conditions. In practice, the swinging of the frame C should be limited to comparatively small angles, represented substantially by the extent of the 65 conducting segments Q . This is accom-

plished readily by regulating corresponding 70ly, the speed of the rotating shafts L and electromagnets H' . However, under unusual circumstances, the reactive force of the stabilizer may be insufficient, and in such 75 cases it may be advisable to hold the frame C against turning about the axis of the bearings B' until the unusual disturbance has passed. The locking device employed for this purpose is operated, in the construction shown in Figs. 1, 2, 3, and 6, whenever the swing of the frame C about the trunnions C' is sufficient to carry the brush P not only beyond the lower edge of the upper 80 segment Q , but into contact with the lower segment Q' . When this occurs, the following circuit will be closed: Battery X , wires c, d (the switch Z being in the closed position, and not in the open position appearing in Fig. 2), conducting segment Q' , brush P , 85 and back to the battery through the wire b . In passing through the wire c , the current energizes the relay Y , so as to establish an electrical connection between the contacts e, f and thus close the following circuit: Main j , wire i , contacts f and e , wire g , binding post N and coil H'' of the corresponding 90 stationary electromagnet H , core of said magnet, shaft L , bearing M , and back to the other main j' through the wire k . The electromagnet H being thus energized, will 95 attract the pulley G and bring it into engagement with the clutching or locking surface of the magnet, thus holding the pulley against rotation, and since this will also 100 positively stop the movement of the belt F , the pulley E and the frame C will be held against turning about the axis of the bearings B' . The pulley G will not be released from the magnet H until the brush P comes 105 out of engagement with the conducting segment Q' ; the left-hand spring K (Fig. 3) will then restore said pulley to the normal central position and leave the pulley E and frame C free to turn about the axis of the 110 bearings B' . If for any reason it is desired to dispense with the locking action controlled by the electromagnet H , the switch Z is brought to the open position shown in Fig. 2, in which case the action will be 115 just as if the segments Q' , electromagnets H , and the electrical connections of such stationary electromagnets were omitted. Of course, if the locking action is not desired at all, the segments Q' , electromagnets H , and the wires, etc., connected with 120 said electromagnets could be omitted altogether. By providing the switch Z (located on the captain's bridge or at any other convenient point of the ship), I am enabled to 125 use the apparatus either with or without the locking action, as desired. As will be seen in Fig. 2, the conducting segments Q, Q' are arranged reversely on the two sides 130 of the apparatus, and the two shafts L ro-

tate in opposite directions, so that the drive belts F on the two sides will move in opposite directions as indicated. Of course, only one of the belts F will be operative at a time.

5 In the construction described above, the current flowing through the brushes P is not the same as the one that energizes the electromagnets H, H', but of course this is not essential to my invention, and the same 10 current (that is, the current of the battery X) might be used to energize the electromagnets. In this case, the apparatus would be simplified greatly, since I would omit the relays Y, Y', Y'', Y*, also the wires 15 c, c', c'', c*, e, e', e'', e*, f, f', f'', f*, g, g', g'', g*, i, i', i'', i*, j, j', and k, k'. In addition, there would be substituted the following 20 connections: Each of the conducting segments Q would be connected with the corresponding contact spring W; each of the bearings M would be connected with the battery X on the side opposite to that connected with the wires b, b', and the two 25 members or terminals of the switch Z would be connected with the binding posts N of the stationary electromagnets H. The operation 30 would be substantially the same as described above, except that the contact of one of the brushes P with the segment Q (or Q', with the switch Z closed) would energize the corresponding magnet H' (or H respectively) directly, without any relay action.

The lower part of the frame C, as shown 35 in Fig. 1, may be somewhat heavier than its upper part, so as to give the frame a tendency to gravitate to a definite normal position.

40 In the form of my invention illustrated by Figs. 4, 5, and 7, the parts A, B, B', C, D, D', R, S, T, U, P', P, Q are exactly the same as in the form first described, and have therefore been shown only in part. The support R carries only one conducting 45 segment, Q. The extended trunnions C' are adapted to engage, when the ship or other body swings transversely, a socket m located at each side of the apparatus, in such a position as to align with said trunnion at the time of engaging it. Said socket m is secured rigidly to stationary supports n, n', and is formed at the end of a pin m' carrying a stationary flanged sleeve o, with its end plate o'. On this sleeve are mounted 50 loosely the pulley E'' and the ratchet wheel p rigidly secured to said pulley. A constantly moving belt F'', driven in any suitable manner, causes the pulley E'' and the ratchet p to rotate constantly, the two belts F'' at the opposite sides of the apparatus traveling in opposite directions, just as indicated for the belts F in Fig. 2. The teeth 55 of each of the ratchet wheels p (it being understood that the arrangement shown in Fig. 4 is provided at the other side of the

apparatus also) are adapted for driving engagement with a pawl q pivoted at r upon an arm or bracket r secured rigidly to the adjacent trunnion C'. One end of the pawl is drawn toward the normal, raised 70 position shown in Fig. 5, by the action of a spring s, the other end of the pawl carries an armature q' adapted to be attracted (against the action of the spring s) by an electromagnet H³ carried by said arm r. 75 Wires t, t' respectively connect the two terminals of the magnet coil, with the brush P and one pole of a source of electricity X' respectively, the other pole of said source of electricity (battery) being connected by 80 a wire t'' with the binding post S of the conducting segment Q.

When a transverse swing of the ship or other body to which the apparatus is attached, brings the socket m into axial alignment with the adjacent trunnion C', and slightly before this moment establishes contact between the brush P and the conducting segment Q, the following action takes place: First, the current of the battery X' is sent 90 through the circuit of the electromagnet, from one pole to wire t'', segment Q, brush P, wire t, electromagnet H³, and back to the battery through the wire t'. The magnet being thus energized, the pawl q is brought 95 from the position shown in full lines (Fig. 5) to that indicated by dotted lines. If the pawl remained in the position shown in full lines, it would never be in mesh with the teeth of the ratchet p, even when the trunnion C' is entirely within the socket m; Fig. 5 shows the trunnion C' in a position shortly before it comes into engagement with the bottom of the socket m, and the dotted lines indicate clearly that the pawl q, 100 when attracted by the electromagnet H³, will be projected into the path of the rotating ratchet teeth, so as to couple said wheel p with the arm r, the trunnion C', and the frame C, to produce precession with the same effect as described in connection with the form of my invention shown in Figs. 1, 2, 3, and 6. As the ship or other body swings back to the normal position, the trunnion C' and socket m will come out of contact, and at the same time the brush P will 105 come out of contact with the segment Q, so that the magnet H³ will become de-energized. The pawl q will thus become disengaged from the ratchet wheel p, so that during the return swing, the precession will be due no longer to the action of the positively driven ratchet wheel p, but to the engaging member T, in a manner similar to the one described in connection with Figs. 1, 2, 3, and 6. The insulating sleeve P' employed in connection with the brush P, in each of the constructions illustrated, is not absolutely essential, since the wire connected with the brush might simply lead to the 110

fulcrum A, in case the brush is not insulated, but in conducting connection with said fulcrum through the trunnion and the carrier B.

5 While each of the constructions shown embodies an electrically controlled clutch, which in the case of Figs. 4 and 5 is formed by the ratchet wheel *p* in conjunction with the electrically controlled pawl *q*, various 10 modifications may be adopted without departing from the nature of my invention as set forth in the appended claims.

I claim as my invention:

1. In a body capable of oscillation, the 15 combination, with a gyroscope structure movably connected thereto, of an operating device comprising a driven member carried by said structure, a driving member, and electrically controlled means brought into 20 action by the swinging of the body, for establishing an operating connection between said members.

2. The combination with a body, of a gyroscope structure capable of a swinging 25 movement relatively thereto, a driven member carried by said structure, a driving member carried by the body, and electrically controlled means for establishing an operating 30 connection between said driving and said driven members.

3. The combination with a gyroscope and a swinging support therefor, of a member carried by said support and adapted to be driven with the gyroscope about an axis 35 other than the gyroscope's axis of spin, a driving member, and electrically controlled means for establishing an operating connection between said members.

4. In a device for stabilizing a body, a 40 gyroscope structure capable of a swinging movement relatively thereto, a driven member carried by said structure, a driving member, and a clutch, brought into action by the tendency of the body to deviate from 45 its position of equilibrium, for establishing an operating connection between said driving and said driven members.

5. In a body subject to angular deviations, a structure capable of a swinging movement 50 relatively to the said body and comprising a frame and a gyroscope mounted therein, a member rotatable with said frame, a driving member normally out of engagement with said rotatable member, and electrically controlled means, brought into action by the angular deviation of the body, for establishing an operating connection between said driving and said rotatable members.

6. In a body to be stabilized, a structure 60 capable of a swinging movement relatively thereto, a gyroscope mounted in said structure, moving devices adapted to co-operate with said gyroscope, which moving devices are partly carried by the said structure and 65 partly by the body, said moving devices be-

ing normally out of operative engagement with one another, and electrically controlled means for effecting such engagement.

7. In a body subject to angular deviations, a structure capable of a swinging movement 70 relatively to the said body, a gyroscope mounted in said structure, moving devices adapted to co-operate with said gyroscope, said moving devices being carried by the body and normally out of operative engagement 75 with the said structure, and electrically controlled means for effecting such engagement.

8. In a gyroscopic stabilizer of a body, a structure capable of a swinging movement 80 relatively to the said body, a gyroscope mounted on said structure, moving devices adapted to co-operate with said gyroscope, said moving devices being carried by the body and normally out of operative engagement 85 with said structure, and a clutch for effecting such engagement.

9. In a body subject to angular deviations, a structure capable of a swinging movement 90 relatively thereto and comprising a gyroscope, and electrically controlled means adapted to engage said structure as the body tends to deviate from its normal position, to produce precession of the said gyroscope.

10. In a body subject to angular deviations, the combination with a structure capable of a swinging movement relatively thereto and comprising a gyroscope mounted for precession at a right angle to said swinging movement, of an electrical device 100 responsive to the angular deviations of the said body, and continuously actuated means, controlled by the said device, for producing precession of predetermined speed.

11. In a body subject to angular deviations, a structure capable of a swinging movement relatively thereto and comprising a gyroscope mounted for precession at a right angle to said swinging movement, a device responsive to the angular deviations 110 of the said body, and electrically controlled means, co-operating with said device, for producing precession of predetermined speed.

12. In a gyroscopic stabilizer of a body 115 comprising a gyroscope having three degrees of rotational freedom, continuously actuated, electrically controlled, means for producing precession, and means, responsive to said precession, for exerting a stabilizing couple 120 on the said body.

13. In a body subject to angular deviations, a structure capable of a swinging movement relatively thereto and comprising a gyroscope, electrically controlled means 125 for producing precession of the said gyroscope, and means for regulating said precession.

14. In a gyroscopic stabilizer, of a body comprising a gyroscope having three degrees 130

- of rotational freedom, continuously actuated, electrically controlled, means for producing precession, said means being automatically responsive to the swinging movement of the body, and means for regulating the said precession.
15. In a body subject to angular deviations, a structure capable of a swinging movement relatively thereto and comprising a gyroscope, an electrically controlled device responsive to the angular deviations of the body, and independently actuated means, co-operating with said device, for producing precession of the gyroscope.
16. In a body to be stabilized, a gyroscope structure capable of a swinging movement relatively thereto, driving members carried by the said body, electrically controlled means for bringing said driving members into operative engagement with the said structure, and means for actuating said driving members.
17. In a body subject to angular deviations, a structure movably connected thereto and comprising a gyroscope, actuating members carried by the said body, and electrically controlled means, responsive to the angular deviations of the said body, for bringing said actuating members into operative engagement with portions of the said structure.
18. The combination with a body, of a gyroscope connected therewith in such a manner as to give the gyroscope rotor three degrees of rotational freedom relatively to the said body, one of said degrees of rotational freedom being limited, and electrically controlled means for producing precession of the said gyroscope as the limit of said limited degree of rotational freedom is reached.
19. The combination with a body, of a gyroscope possessing three degrees of rotational freedom relatively thereto, one of said degrees of rotational freedom being limited, means for producing precession of the said gyroscope as the limit of said limited degree of rotational freedom is reached, a clutch mechanism for controlling said means, and means for actuating said clutch mechanism.
20. In a body subject to angular deviations, a structure having a limited degree of rotational freedom relatively thereto and comprising a gyroscope, means for producing precession of the said gyroscope as the limit of said degree of freedom is reached, a clutch mechanism for controlling said means, and means responsive to the angular deviations of the body, for automatically controlling said clutch mechanism.
21. The combination with a body, of a gyroscope spinning about one of its axes, adapted to precess about a second axis, and having a limited degree of rotational freedom about a third axis, and electrically controlled means for producing precession of the said gyroscope about said second axis as the limit of said rotational freedom is reached.
22. The combination with a body, of a gyroscope spinning about one of its axes, adapted to precess about a second axis, and having a limited degree of rotational freedom about a third axis, means for producing precession of the said gyroscope as the limit of said rotational freedom is reached, a clutch for controlling said means, and means for regulating said precession.
23. In a body subject to angular deviations, a structure having a limited degree of rotational freedom relatively thereto and comprising a gyroscope, an electrical control device responsive to the angular deviations of the body, means controlled by said device for causing said gyroscope to precess as the limit of said rotational freedom is reached, for exerting a stabilizing couple on the said body.
24. In a body subject to angular deviations, a gyroscope structure capable of a swinging movement relatively thereto, a driven member mounted to move with a portion of said structure, a driving member, a circuit closer comprising elements carried respectively by the said body and the said structure and adapted to co-operate with each other in response to the angular deviations of the body, and means controlled by the said circuit closer for establishing an operating connection between said driving and said driven members.
25. In a body to be stabilized, the combination with a structure having a limited degree of rotational freedom relatively thereto and comprising a gyroscope, of an operating device comprising a circuit closer having one of its elements fixed relatively to the body and the other element fixed relatively to the said structure, and means, controlled by the said circuit closer, for causing said gyroscope to precess as the limit of said degree of freedom is reached.
26. The combination with a body and a structure capable of angular deviation relatively to one another, of an operating device comprising two driven members carried by said structure and located at opposite sides thereof, driving members, and electrically controlled means, responsive to said angular deviation, for establishing a driving connection between an operating member and the corresponding driven member.
27. In a body to be stabilized, the combination with a structure having a limited degree of rotational freedom relatively thereto and comprising a gyroscope, of a pair of circuit closers located at opposite sides of the said structure, each circuit closer comprising an element fixed relatively to the body

and an element fixed relatively to said structure, and means, controlled by said circuit closers, for causing said gyroscope to precess as the limit of said degree of freedom is reached.

28. The combination with a body and a structure capable of a swinging movement relatively to one another, of an operating device responsive to said relative movement 10 and comprising driven members carried by the said structure and located at opposite sides thereof, driving members moving in opposite directions, circuit closers located at opposite sides of the said structure, each 15 circuit closer comprising an element fixed relatively to the body and an element fixed relatively to said structure, and means, controlled by the said circuit closers, for establishing an operating connection between 20 one of the said driving members and the corresponding driven member.

29. In a body to be stabilized, the combination with a structure having a limited degree of rotational freedom relatively to the 25 said body when the body is in equilibrium and comprising a gyroscope, of an operating device comprising a multiplicity of circuit closers made operative by the incipient deviation of the body from said position of 30 equilibrium, which deviation is adapted to check said limited degree of freedom, and means, controlled by said circuit closers, for causing said gyroscope to precess.

30. In a gyroscopic stabilizer, the combination, with a gyroscopic rotor, a frame in which it is journaled, a carrier pivotally connected with the body to be steadied and supporting said frame to swing about an axis transverse to the pivot axis, driven members 40 located on opposite sides of said frame and mounted to move in unison therewith, circuit-closer elements likewise located on opposite sides of said frame and mounted to move in unison therewith, driving members 45 moving in opposite directions, co-operating circuit-closer elements mounted on said body and adapted for contact with the first-named circuit-closer elements during oscillations of the said body, and means, controlled by said 50 circuit-closers, for establishing a driving connection between one or the other of said driving members and the corresponding driven member.

31. In a gyroscopic stabilizer, the combination, with a gyroscopic rotor, a frame in which it is journaled, a carrier on which said frame is mounted to swing about an axis transverse to the rotor axis, said carrier being fulcrumed on the body to be steadied, the 60 fulcrum axis being transverse to the axis about which the frame swings relatively to the carrier, driven members carried by said frame on opposite sides of the fulcrum, driving members carried by said body, circuit-

closer elements carried by said frame on opposite sides of the fulcrum, and co-operating circuit-closer elements carried by said body and converging toward the side on which the fulcrum is located, and means, controlled by said circuit-closers, for establishing a driving connection between one or the other of said driving members and the corresponding driven member.

32. In a body subject to angular deviations, a gyroscope structure capable of a 75 swinging movement relatively thereto, a driven member carried by the said structure, a driving member, electrically controlled means for establishing an operating connection between said driving and said driven 80 members, and a contact member carried by the body and adapted to make contact with said structure substantially at the same moment that the aforesaid connection is established.

33. In a body subject to angular deviations, a gyroscope structure movably connected thereto, a driven member carried by said structure, a driving member carried by the body, a clutch mechanism for establishing an operating connection between said driving and said driven members, and contact members carried by the body and adapted to engage the said gyroscope structure as the body deviates from its normal position.

34. In a body subject to angular deviations, a gyroscope structure capable of a swinging movement relatively thereto, moving devices carried by the body and normally out of operative engagement with the said structure, electrically controlled means for effecting such engagement, and resilient contact members carried by the body and adapted to engage the said structure as the body deviates from its normal position.

35. In a body subject to angular deviations, a structure capable of a swinging movement relatively thereto and comprising a gyroscope, contact members carried by the body and adapted to engage said structure as the body deviates from its normal position, and electrically controlled means, co-operating with the said contact members, for producing precession of the said gyroscope.

36. In a body subject to angular deviations, a structure movably connected thereto and comprising a gyroscope, electrically controlled means for producing precession of the said gyroscope, and contact members carried by the body and adapted to engage the said structure, to produce another precession of the said gyroscope.

37. In a body subject to oscillations, a gyroscope structure movably connected thereto, electrically controlled contact members carried by the body and adapted to

engage the said structure, and yielding devices for checking the impact between the said body and the said structure at the time of such engagement.

5 38. In a body subject to angular deviations, a structure capable of a swing movement relatively thereto and comprising a gyroscope, electrically controlled means for producing precession of the said gyroscope as the angular deviation of the body causes the body to come in contact with portions of the said structure, and resilient devices for checking the impact between the body and the said portions of the said structure.

10 39. The combination with a body, of a gyroscope structure movably connected thereto, electrically controlled members carried by said body, co-operating electrically controlled members carried by said structure and adapted to make contact with said first mentioned members, and resilient means for checking the impact between said members carried by the body and said co-operating members carried by the structure at the time 20 of such contact.

25 40. In a body subject to angular deviations, a structure capable of a swinging movement relatively thereto and comprising a gyroscope, electrically controlled means for producing precession of predetermined speed, and contact members carried by the body and adapted to engage the said structure, for producing normal precession of the said gyroscope.

30 41. In a body subject to angular deviations, a structure movably connected thereto and comprising a gyroscope, driving members carried by the body, means for actuating said driving members, electrically controlled means for effecting an operating engagement between said driving members and the said structure, to produce precession of the said gyroscope at a predetermined rate, and contact members carried by the body 40 and adapted to engage said structure, to produce normal precession of said gyroscope.

35 42. In a body to be stabilized, a structure capable of a swinging movement relatively thereto and comprising a gyroscope, moving devices carried in part by the body and in part by said structure and normally out of operative engagement with one another but adapted to become operatively engaged, a clutch mechanism for regulating said engagement, and contact members carried by the body and adapted to engage said structure, said contact members co-operating with said moving devices to produce precession of said gyroscope when such engagement is effected.

40 43. In a body subject to angular deviations, the combination with a structure capable of a swinging movement relatively thereto and comprising a gyroscope mount-

ed for precession at a right angle to said swinging movement, of means responsive to said angular deviations for producing precession of the gyroscope, and means for locking said gyroscope against precession when said angular deviations tend to exceed a certain predetermined limit.

44. The combination with a gyroscope having three degrees of rotational freedom, of means for producing precession of the gyroscope, and means for locking said gyroscope when said precession exceeds a certain predetermined limit.

45. In an apparatus for stabilizing a body, the combination with a structure capable of a limited swinging movement relatively thereto and comprising a gyroscope mounted for precession at a right angle to said swinging movement, of means, brought into action by the precession of the gyroscope, for exerting a torque on the body, and means for checking said torque when said precession exceeds a certain predetermined limit.

46. In a stabilizing apparatus, the combination with a gyroscope having three degrees of rotational freedom, of means for producing precession of the gyroscope, and electrically controlled means for locking said gyroscope against precession.

47. In an apparatus for stabilizing a body against external torques, the combination with a structure capable of a limited swinging movement relatively thereto and comprising a gyroscope mounted for precession at a right angle to said swinging movement, of means, brought into action by the precession of the gyroscope, for opposing said external torques, and means for automatically locking the gyroscope when said external torques exceed a certain predetermined limit.

48. In a body stabilizer, the combination, with a gyroscope and a support therefor, of a driven member mounted to move with said support, a driving member carried by said body and operatively connected with said driven member, a rotary electromagnet adapted to attract said driving member to form a clutch connection therewith, and means, controlled by oscillations of the body, for energizing said electromagnet.

49. In an apparatus for stabilizing a body against external torques, the combination with a gyroscope structure, of a driving member carried by the body, a driven member carried by said structure, a clutch mechanism for actuating said driving member, a brake mechanism adapted to lock said driven member, means, responsive to said external torques, for energizing said clutch mechanism, and means for energizing said brake mechanism when said external torques exceed a predetermined limit.

50. In a gyroscopic stabilizer, the combi-

nation, with a gyroscopic rotor and a support therefor loosely connected with the body to be steadied, of a driven member mounted to move in unison with said support, an armature-pulley carried by said body and operatively connected with said driven member, a rotary electromagnet and a stationary electromagnet located on opposite sides of said pulley and adapted for engagement therewith, and a double circuit-closer, adapted to be brought into operation by oscillations of said body, and comprising two members arranged to come into action successively and in actuating relation to the respective electromagnets.

51. In a body subject to angular deviations, the combination with a gyroscope structure, of a driving member carried by the body, a driven member carried by said structure, a clutch mechanism for actuating said driving member, a brake mechanism adapted to lock said driven member, means for keeping said driving member out of operative engagement with said driven member when the body is in its normal position, means for energizing said clutch mechanism when the body deviates from its normal position, and means for energizing said brake mechanism when said angular deviations of 30 the body exceed a certain predetermined limit.

52. In an apparatus for stabilizing a body and comprising a gyroscope having three degrees of rotational freedom, electrically controlled means for producing precession of the gyroscope, a precession locking device, and means for energizing said locking device when the precession of the said gyroscope exceeds a certain predetermined limit.

53. In a body subject to angular deviations, a gyroscope having three degrees of rotational freedom, means for producing precession of said gyroscope, a clutch mechanism for controlling said means, a precession locking device, circuit closers made operative by the angular deviations of said body, and means, controlled by said circuit closers, for energizing said clutch mechanism or said locking device.

54. In a gyroscopic stabilizer, the combination, with a gyroscopic rotor and a support therefor loosely connected with the body to be steadied, of a driven pulley and a counterbalancing pulley both mounted to move in unison with said support, a driving pulley located at one side of said support and connected with the driven pulley, an idler pulley located at the other side of the support and connected with the counterbalancing pulley, and means, brought into action by oscillations of said body, for establishing a driving action on said driven member.

55. A gyroscopic stabilizer comprising a gyroscope mounted for three degrees of rotational freedom, power means for governing the precession of said gyroscope, and a limit device for causing said power means to stop.

56. A gyroscopic stabilizer comprising a gyroscope mounted for three degrees of rotational freedom, power means for governing the precession of said gyroscope, and a limit device on said gyroscope for rendering said power means inoperative.

57. A gyroscope mounted for three degrees of rotational freedom, means for braking said gyroscope about a precessional axis, and means responsive to precession beyond a predetermined limit for applying said braking means.

58. In a body subject to angular deviations, a gyroscopic stabilizer comprising a gyroscope mounted for three degrees of rotational freedom, power means for governing the precession of said gyroscope, means responsive to said angular deviations for controlling said power means, and additional means for automatically rendering said power means inoperative.

59. In a body subject to angular deviations, a gyroscopic stabilizer comprising a gyroscope mounted for three degrees of rotational freedom, power means for governing the precession of said gyroscope, means responsive to said deviations for controlling said power means, and additional means responsive to excessive deviations of said body for automatically cutting out said power means.

60. In a body subject to angular deviations, a stabilizer comprising a structure capable of swinging movement relatively to said body and comprising a gyroscope mounted for precession at a right angle to said swinging movement, power means for governing the precession of said gyroscope, means responsive to said deviations of said body for controlling said power means, and additional means for automatically cutting out said power means and applying a brake about the axis of said precession.

61. In a body subject to angular deviations, a structure capable of limited swinging movement relatively thereto and comprising a gyroscope mounted for precession at a right angle to said swinging movement, means for governing the precession of said gyroscope, and a controller therefor operated by said angular deviations.

62. In a body subject to angular deviations, a gyroscope mounted for three degrees of rotational freedom, means for governing the precession of said gyroscope, a normally inoperative brake adapted to brake said gyroscope about its axis of precession, and automatic means for cutting out said pre-

cession governing means and applying the brake when said deviations of said body become excessive.

63. In a body subject to angular deviations, a structure capable of swinging movement relatively thereto and comprising a gyroscope mounted for precession at a right angle to said swinging movement, means for

braking said gyroscope about its axis of precession, and means for causing said brake to be applied before and released after reversal of the direction of said angular deviations.

In testimony whereof I have signed this specification.

ALEXANDER S. CHESSIN.
